CLAIM

The ornamental design for a lancing device with transparent
 endcap, as shown and described.

(56) **References Cited**

DESCRIPTION**U.S. PATENT DOCUMENTS**

FIG. 1 is a perspective view of a lancing device with
 transparent endcap according to a preferred form of the
 present invention;

FIG. 2 is a front view of the lancing device with transparent
 endcap of FIG. 1;

FIG. 3 is a back view of the lancing device with transparent
 endcap of FIG. 1;

FIG. 4 is a first side view of the lancing device with
 transparent endcap of FIG. 1;

FIG. 5 is a second side view of the lancing device with
 transparent endcap of FIG. 1;

FIG. 6 is a rear end view of the lancing device with
 transparent endcap of FIG. 1; and,

FIG. 7 is a forward end view of the lancing device with
 transparent endcap of FIG. 1.
